ALBERT M. WALKER

INVENTOR.

BY Thomas J. Wallace

ATTORNEY.

UNITED STATES PATENT OFFICE

130,146

DESIGN FOR A PLATE OR SIMILAR ARTICLE

Albert M. Walker, Akron, Ohio, assignor to The Bailey-Walker China Co., Bedford, Ohio

Application August 20, 1941, Serial No. 102,964

Term of patent 7 years

To all whom it may concern:

Be it known that I, Albert M. Walker, a citizen of the United States of America, residing at Akron, in the county of Summit and State of Ohio, have invented a new, original, and ornamental Design for a Plate or Similar Article, of which the following is a specification, reference being had to the accompanying drawing, forming part thereof, wherein the figure of the drawing is a top plan view of a plate or similar article, showing my new design.

I claim:

The ornamental design for a plate or similar article, substantially as shown.

ALBERT M. WALKER.
